MUFFLER FOR PNEUMATIC PICK HAMMERS
AND LIKE TOOLS

Oscar Jean Henri Cherain, Jemeppe-sur-Meuse,
Belgium

Application July 25, 1947, Serial No. 763,489
In Belgium July 31, 1946

1 Claim. (Cl. 181—36)

1

My invention relates to muffler for pneumatic pick-hammers and like tools and has reference particularly to improvements to said apparatus in order to suppress as far as possible the production of cloud of dust when working with a pick-hammer.

An object of my invention is to provide a device applied to the pick-hammer and reducing the pressure of the fluid at its exhaust from the tool, to such an extent as will obviate any swirling of the dust.

A further object is to provide at the free end of the turning sleeve in which the needle fits, a piece that forms a fluidtight joint with the needle which passes through it.

A still further object is to provide a needle having a cup-shaped or crescent-shaped cross section, the two cutting edges of which are separated from one another by a single groove.

My invention will be more fully described hereinafter with reference to the accompanying drawings, in which:

Figure 1 is a view of the pick-hammer, partly in longitudinal elevation but mainly in section;

Figure 2 is a cross section on the line A—B in Figure 1;

Figure 3 is a back view of the handle of the hammer, showing the angular position of the pressure-reducing device in relation to the axial plane of the hammer;

Figure 4 is a section on the line C—D in Figure 1;

Figure 5 is a plan view of the cutting end of the needle; and

Figure 6 is a section on the line E—F in Figure 5, on a scale twice as large.

Figure 7 is a plan view on an enlarged scale of the perforated ring shown in Figure 1.

Figure 8 is a section on the line G—H of Figure 7.

Figure 9 is a plan view on an enlarged scale of the sieve or strainer shown in Figure 1.

Figure 10 is a section on the line I—J of Figure 9.

The pick-hammer to which the improvements provided by this invention are applied is of a known type, to which of course no claim is made in itself.

According to the invention, the socket or sleeve 1 of the handle is provided, at the place where the exhausting of the compressed air into the atmosphere takes place, with a cast-on nozzle or blast-pipe 2, the axis of which makes a definite angle, of 35 degrees for example, with the axis X—Y of the hammer, as indicated in Figure 3.

By this, the air leaving the nozzle 2 is directed downwards and to the side, so that it cannot be deflected, which would cause a strong impulsive reaction, but is directed downwards, which is the best way to obtain a different effect, as will be seen from the following description.

3 The nozzle 2 is provided with a sleeve or nozzle 3, which is screwed on to the body 5 of the hammer.

4 The sleeve 3 is provided with a threaded union or coupling member 4, which is screwed on to the body 5.

5 The body 5 is provided with a tubular body 6 of cast iron, Duralumin or the like, provided internally with triangular ribs 6, so arranged relatively to one another as to form baffle plates.

6 At its other end the body 5 terminates in a sleeve or socket 7, in which is fixed a small sieve or strainer 8. This socket 7 tapers outwards to a

7 beak or jet 9 shaped like the barrel of a whistle, the aperture of which may be cut transversely by a rib.

8 The compressed air expelled by the distributing valve of the pick-hammer flows through the nozzle 2, encountering a cross-bar 10 inserted in the latter with a view to deflecting the current of compressed air.

9 Next it enters the body 5, where its pressure is greatly reduced under the influence of the opposite ribs 6, and then of the screen 8,

10 and finally it escapes into the atmosphere through the mouth or jet 9. This air therefore leaves the pick-hammer towards the rear of the latter, but laterally in relation to the workman who is operating it, so that its pressure, being considerably

11 diminished, is insufficient to cause eddies of air capable of raising the dust produced by the hammer and forming whirling eddies that would be injurious to the operator.

12 The same end in view the turning sleeve 11, which is screwed on to the body 12 of the pick-

13 hammer in order to cover the needle 13, is screw-

14 threaded at its end at 14 to receive a conical

15 piece 15 through which the said needle passes.

16 The fluid tightness of the assemblage is ensured

17 on the one hand by an india-rubber ring 16 inter-

18 posed between the sleeve 11 and the conical piece

19, and on the other hand by a ring 17 of metal,

20 anti-friction material or the like between this

21 conical piece and the needle 13.

22 Finally the needle 13 itself has only two cutting

23 edges 18, separated from one another on one side

24 by a longitudinal groove 19, the outline of the

25 cross section being completed by a substantially

26 semi-circular part 20. This being so, the needle

27 13, in working, does not produce dust, as is the

28 case with the four cutting edges of the usual

29 needles, but granules, of coal for example, the

30 weight of which is too great for toxic clouds to

31 form under the action of the compressed air, es-

32 pecially at a reduced pressure.

33 Having thus described my invention, what I

34 claim as new, and desire to secure by Letters

35 Patent is:

36 A muffler for pneumatic hammers and like tools,

37 consisting of a hollow body carried by the tool,

aid hollow body having internal baffles and a reduced cross-section at its ends, each of which is provided with a screen to reduce the pressure of the fluid exhaust, a fluid outlet orifice formed in said hollow body being directed rearwardly of the slot at a predetermined angle with respect to the latter.

OSCAR JEAN HENRI CHERAIN.
